(57) **CLAIM**

The ornamental design for a pivoting tower for antenna, as shown and described.

DESCRIPTION

FIG. 1 is a perspective view of a pivoting tower for antenna showing our design in a horizontal position;

FIG. 2 is a front view of the pivoting tower for antenna of FIG. 1;

FIG. 3 is a back view of the pivoting tower for antenna of FIG. 1;

FIG. 4 is a top view of the pivoting tower for antenna of FIG. 1;

FIG. 5 is a bottom view of the pivoting tower for antenna of FIG. 1;

FIG. 6 is a left side view of the pivoting tower for antenna of FIG. 1;

FIG. 7 is a right side view of the pivoting tower for antenna of FIG. 1;

FIG. 8 is a perspective view of a pivoting tower for antenna showing our design in a vertical position;

FIG. 9 is a front view of the pivoting tower for antenna of FIG. 8;

FIG. 10 is a back view of the pivoting tower for antenna of FIG. 8;

FIG. 11 is a top view of the pivoting tower for antenna of FIG. 8;

FIG. 12 is a bottom view of the pivoting tower for antenna of FIG. 8;

FIG. 13 is a left side view of the pivoting tower for antenna of FIG. 8; and,

FIG. 14 is a right side view of the pivoting tower for antenna of FIG. 8.

The broken lines in the figures depict portions of the pivoting tower for antenna that form no part of the claimed design.
